UNITED STATES PATENT OFFICE.

KARL A. TERVO, OF WEST QUINCY, MASSACHUSETTS.

COW-MILKER.

1,105,468.

Specification of Letters Patent. Patented July 28, 1914.

Application filed March 27, 1914. Serial No. 827,684.

To all whom it may concern:

Be it known that I, KARL A. TERVO, a citizen of the United States, residing at West Quincy, in the county of Norfolk and State of Massachusetts, have invented new and useful Improvements in Cow-Milkers, of which the following is a specification.

This invention relates to cow milkers, and it consists in the novel features hereinafter described and claimed.

An object of the invention is to provide a milker of simple structural arrangement adapted to be easily and readily applied to the udder and teats of a cow and adapted to be readily operated to accomplish the milking operation.

With the above object in view, the invention comprises a receptacle having curved sides against which the teats may be arranged. Crank shafts are journaled for rotating in the receptacle and are operatively connected together whereby they turn in unison. The said shafts are provided upon their cranks with soft resiliently supported members which are adapted to pass along as the shafts are rotated and which accomplish the sucking operation.

In the accompanying drawings: Figure 1 is a top plan view of the milker. Fig. 2 is a vertical longitudinal sectional view of the same. Fig. 3 is a transverse sectional view of the same. Fig. 4 is an end elevation of the same with parts broken away and parts in section. Fig. 5 is a detailed view of one of the crank shafts of the milker with parts thereof disconnected and parts in section.

The milker comprises a receptacle 1 having outwardly curved opposite sides 2 which merge at their lower portions into a transversely curved bottom 3. The receptacle 1 is closed at one end by means of a wall 4 which is preferably of wood and at its other end by a wall 5 which may be of sheet metal or other suitable material. A nipple 6 passes through the bottom 3 of the receptacle 1 and the end of a flexible hose (not shown) may be passed over the end of the nipple. A casing 7 is located at that end of the receptacle which is provided with the wall 5 and the said casing is normally closed at its outer end by means of a detachable wall 8 preferably of wood. The wall 8 is held in position at the end of the casing by means of a bolt 9 which passes transversely through the sides of the casing and which extends along a groove provided at the upper edge

of the said wall 8. The wall 8 is provided at its lower edge with a pin 10 which is adapted to fit in a perforation provided at the bottom of the casing 7. Bail handles 11 are pivoted at the upper edges of the side 2 of the receptacle 1 and coiled springs 12 are connected at their lower ends with the upper edge portions of the walls 2 of the receptacle 1 and the said springs are arranged in pairs which are located one in the vicinity of each end of the receptacle 1. The upper ends of the members of each pair of springs 12 are connected with a link 13 and a belt 14 passes through the link 13 and is adapted to be passed over the back of the animal whereby the receptacle 1 may be held up in position against the udder. A bar 15 is located at the top of the receptacle 1 midway between the side walls 2 and traverses the length of the said receptacle. This bar is intended to divide the teats when the receptacle is applied to the udder and furthermore will prevent the teats from being crossed while they are in the receptacle.

A bearing plate 16 is provided in the wall 4 and a bearing plate 17 is provided in the wall 8. Crank shafts 18 are journaled in the bearings of the plates 16 and 17 and the cranks of said shafts are located in the receptacle 1 between the walls 1 and 5 thereof. The cranks of the shafts 18 are made in sections and the said sections are secured together by means of securing devices 19 and when the sections are separated from each other the members which are mounted upon the cranks may be readily removed therefrom as will be hereinafter described. Gear wheels 20 are mounted upon the shafts 18 between the walls 5 and 8 and the said wheels mesh with each other. A crank handle 21 is fixed to one of the shafts 18 and may be used for turning the shaft. Through the intermeshing gear wheels 20 as one shaft 18 is turned the other shaft 18 is turned in an opposite direction.

Sleeves 22 are loosely mounted upon the cranks of the shafts 18 and are provided at their ends with flanges 23. Cylinders 24 are mounted upon the flanges 23 and the said cylinders are of soft flexible material as for instance soft rubber. Springs 25 are located in the cylinders 24 and approximately traverse the length thereof. The said springs surround the cranks of the shafts 18. The springs 25 are formed with a succession of convolutions which extend from end to end

of the springs and the said convolutions surround the intermediate portions of the said crank. The convolutions of the springs 25 are not all of the same diameter but some 5 of the said convolutions snugly receive the intermediate portions of the cranks 18 while other of the said convolutions have contact with the inner surfaces of the cylinders 24. The convolutions which are intermediate in 10 diameter between the larger and smaller convolution are spaced normally both from the shafts and the inner surfaces of the cylinders 24. The cranks of the shaft 18 are so arranged with relation to each other that 15 when one crank is vertically above the axis of its shaft the other crank is vertically below the axis of the other shaft and inasmuch as the shafts 18 rotate in opposite directions the periphery of the cylinder 24 mounted 20 on one shaft will be carried across the axis of the other shaft and vice versa as the said shafts rotate. During the milking operation and as the shafts 18 are rotated the cylinders 24 move from the upper portion of 25 the receptacle 1 down along the inner surfaces of the walls 2 of the said receptacle, but spaced from the said walls and then may move up along the intermediate portion of the receptacle 1 to the upper portion 30 thereof.

When the milker is applied to the cow as hereinbefore described and the shafts 18 are rotated whereby the cylinders 24 are moved as just stated, the said cylinders encounter 35 the teats and press the same against the inner surfaces of the outwardly curved side walls 2 of the receptacle 1. The said cylinders move down along the teats and force the milk from the same which passes down 40 upon the bottom 3 and thence out of the receptacle 1 through the nipple 6. Owing to the flexibility of the cylinders 24 and the peculiar configuration of the springs 25 the said cylinders 24 will bear against the teats 45 with sufficient force to extract the milk but the pressure is not excessive or injurious. Furthermore the configuration of the springs 25 is such as to press the soft material of the cylinders 24 partially around the teats

respective of the relative diameter of the 50 teats in order that the pressure may be properly applied. By removing the securing devices 19 the sections of the shafts 18 may be disconnected from each other and after this has been done the sleeves 22 may be slipped 55 longitudinally from the intermediate portions of the cranks of the shafts 18 and thus the parts may be readily separated for cleaning or other purposes.

Having described the invention what is 60 claimed is:—

1. A milker comprising a receptacle having curved walls, crank shafts journaled for rotation in the receptacle, sleeves loosely mounted upon the cranks of the shafts, 65 coiled springs surrounding the sleeves, and cylinders of soft material surrounding the coiled springs.

2. A milker comprising a receptacle having curved walls, crank shafts journaled for rotation in the receptacle, cylinders of soft pliable material surrounding the cranks of the shafts and coiled springs interposed between the cylinders and the cranks of the shafts the convolutions of the coils of said 75 springs varying in diameter.

3. A milker comprising a receptacle having curved walls, crank shafts journaled for rotation in the receptacle, cylinders of soft pliable material mounted upon the cranks 80 of the shafts and springs interposed between the cylinders and the cranks of the shafts said springs having a series of convolutions, the springs extending from end to end of the cylinders, the convolutions of the springs 85 varying in diameter the larger convolutions normally bearing against the inner surfaces of the cylinders, the smaller convolutions snugly receiving the cranks of the shafts and the intermediate convolution being 90 spaced from the cylinders and the shafts.

In testimony whereof I affix my signature in presence of two witnesses.

KARL A. TERVO.
